WAGON DUMPING MECHANISM

Filed Dec. 21, 1933

2 Sheets-Sheet 2

- tated, rotation is imparted to the winch shaft 19 through the gear train 24—23—21—20. The flexible elements 16 are wound on the winch shaft 19, the counter shaft 14 is carried backwardly on 5 the tracks 12, the lifting arms 27 tilt the supporting member 31, on its pivotal mounting 36, to the position of Fig. 3, and the lifting members 28, acting through the links 30, raise the body 11 with respect to the supporting member 10 31, the body moving on the pivotal connection 38—39 which unites it with the supporting member 31. The body 11 may be held in the position specified, by operating the brake 26.

It is clear that if the forked ends 33 of the 15 lifting members 28 were kept clear of the counter-shaft 14, the lifting members would not fulcrum on the countershaft, the links 30 would not be operated, and the rear end of the body 11 would not be raised to the position shown in Fig. 3, 20 when the supporting member 31 is raised to the position of that figure. The means for accomplishing the result last-mentioned will now be described.

The lifting members 28 are connected by a 25 transverse bridge 37. A latch 40 is pivoted at 40' to the forward end of the supporting member 31. The latch 40 is pivoted to an operating member 41, 30 slideable in a guide 41a on the supporting member 31. A pin 42 may be used to connect the operating member 41 to the supporting member 31.

When the parts are in the lowered position of 35 Fig. 1, the forks 33 of the lifting members 28 are behind and clear of the countershaft 14. By means of the operating member 41, the person in charge swings the latch 40 until its rear end is under the bridge 37 on the lifting members 28. Thus, the lifting members 28 are connected to

the forward portion of the supporting member 31, as shown in dotted line in Fig. 3, the lifting members 28 are carried upwardly along with the supporting member 31, the lifting members do not fulcrum on the countershaft 14, the links 30 are not operated, and the rear end of the body 11 does not rise to the position of Fig. 3, when the front end of the body is raised to the position of said figure.

What is claimed is:

In a wagon dumping mechanism, a frame, a rearwardly and upwardly inclined track on the frame, a body carried by the frame, a body-supporting structure pivotally connected to said body at the front of the body and pivotally connected to said frame at the rear thereof, a link pivotally connected at one end to said supporting structure intermediate the ends thereof and at the opposite end to the rear of said body, a transversely extending shaft carried by said track, 20 means for moving said shaft longitudinally of said track, a lifting arm pivotally connected to said shaft at one end and pivotally connected to said supporting structure at the opposite end, whereby when said shaft is moved rearwardly and upwardly along the track said supporting structure will swing said body at the front upwardly, and a straight lifting member pivoted at one end to said link intermediate the ends of the link, the end of said lifting member opposite its connection with said link being forked and normally positioned to be engaged by said shaft and moved rearwardly and upwardly thereby, whereby said link and the rear of said body will be lifted, and the load will be transmitted directly through the 30 forked link from the body to the shaft and track.
